UNITED STATES PATENT OFFICE

CHARLES A. JOSLIN, OF NORTH ATTLEBORO, MASSACHUSETTS

DESIGN FOR A SPOON OR LIKE ARTICLE

Application filed December 8, 1930. Serial No. 37,924. Term of patent 7 years.

To all whom it may concern:

Be it known that I, CHARLES A. JOSLIN, a citizen of the United States, residing at North Attleboro, in the county of Bristol and State of Massachusetts, have invented a new, original, and ornamental Design for a Spoon or like Article, of which the following is a specification, reference being had to the accompanying drawings, forming part thereof.

In the drawings

Fig. 1 is a plan view of the spoon showing my design.

Fig. 2 is a view in cross section on sectional line X—X of Fig. 1.

The dominant feature of my design consists in the ornamentation on the handle of the spoon or like article.

I claim:

The ornamental design for a spoon or like article, as shown and described.

CHARLES A. JOSLIN.
